United States Patent Office

Des. 193,594
Patented Sept. 11, 1962

193,594

BOAT

Henry U. Spence, Painesville, Ohio, assignor, by mesne assignments, to Upson Machine Products, Inc., a corporation of Ohio

Filed Dec. 14, 1960, Ser. No. 63,222

Term of patent 14 years

(Cl. D71—1)

FIG. 1

FIG. 2

FIG. 3

FIG. 4

FIG. 5

FIG. 6

FIG. 1 is a top plan view of a boat embodying my new design;

FIG. 2 is a side elevation the opposite side thereof being substantially the same;

FIG. 3 is a front elevation;

FIG. 4 is a rear elevation;

FIG. 5 is a top perspective view; and

FIG. 6 is a rear perspective view on a slightly enlarged scale.

The bottom of the boat is conventional. The dominant features of my design are shown in solid lines.

I claim:

The ornamental design for a boat, as shown and described.
